UNITED STATES PATENT OFFICE.

JOHN A. WILLIAMS, OF RICHMOND HILL, NEW YORK, ASSIGNOR TO THE WILLIAMS-PURCHAS MANUFACTURING CO., OF MORRIS PARK, NEW YORK, A FIRM COMPOSED OF SAID JOHN A. WILLIAMS, WALTER G. PURCHAS, AND MAUD I. PURCHAS, ALL OF RICHMOND HILL, NEW YORK.

NEEDLE-HOLDER.

1,172,856.

Specification of Letters Patent. Patented Feb. 22, 1916.

Application filed May 21, 1915. Serial No. 29,459.

To all whom it may concern:

Be it known that I, JOHN A. WILLIAMS, a citizen of the United States, and a resident of Richmond Hill, Long Island, in the county of Queens and State of New York, have invented certain new and useful Improvements in Needle-Holders, of which the following is a specification.

The invention is a convenient, compact and attractive device for holding an assortment of needles, the object being to enable the user to keep her needles in one place, each size by itself, and to render the same readily accessible and replaceable.

In the accompanying drawings illustrating the invention: Figure 1 is a perspective view of the holder, shown approximately actual size; Fig. 2 is a longitudinal section through the device, all but one of the tubes being shown in elevation; Fig. 3 is a cross-section, with dotted lines indicating the retainer in open position; and Fig. 4 is a sectional plan view looking down on the tops of the tubes.

The device comprises a thin or flat block 1, preferably of oblong rectangular form, having a series of sockets or openings 2, of varying depth, extending inward from one of its long narrow surfaces. The body of the device also includes a frame 3, comprising side members 4, which are secured by fasteners 5 to the ends of the block, and a cross-member 6 uniting the outer or upper ends of the said side members and provided with a series of openings 7 disposed in alinement with the sockets 2. Tubes 8 are received at their outer or upper portions in the openings 7, and at their inner or lower portions in the sockets 2, and their upper open ends are closed by caps 9, which are disposed above the cross-member 6. These tubes are preferably made of some non-fragile material, for example hard rubber, and are of different lengths, to correspond with the different sizes of needles which are to be accommodated.

Owing to the varying depths of the sockets 2, the capped upper ends of the tubes are brought in transverse alinement, so that all 50 may be held in place by a retainer 10. The latter consists of a bail-shaped frame, the side members 11 of which are pivotally

united at 12 to the side members 4 of the frame 3. The cross-piece 13 of the frame lies adjacent the tops of the caps 9. Spring 55 holding means are provided, keeping the retainer 10 in its normal position, the said means preferably comprising projections 14 forced inward from the side members 11 of the retainer and corresponding depressions 60 15 formed in the side members 4 of the frame 3.

In operation, the members 4 and 11 yield with sufficient readiness to permit the retainer to be swung easily to the position 65 indicated in Fig. 3, the resilience of the parts automatically restoring it to the locking engagement when the retainer is returned to retaining position. The retainer frame keeps the caps 9 from accidentally 70 coming off the tubes, and in the particular embodiment of the invention illustrated, wherein the tubes are removable, also serves to hold the tubes in their sockets. Another function of this frame is to act as an easel 75 support when swung to a downward inclination, so that the device may stand in an inclined position, with the caps uncovered and therefore free to be removed.

The tops of the caps 9 may bear numerals, 80 as shown in Fig. 4, indicating the sizes of the needles contained therein.

What I claim as new is:

1. A holder for needles, comprising a block 1 having a series of sockets 2, a frame 35 3 having side members secured to the ends of the said block and a cross-member 6 provided with a series of openings 7, a series of tubes 8 provided with caps received within said openings and sockets, and a 90 bail-shaped retainer 13 having its side members pivoted to the side members of the frame and its cross-member normally extending over the caps of the tubes.

2. A holder for needles, comprising a 95 block 1 having a series of sockets 2, a frame 3 having side members secured to the ends of the said block and a cross-member 6 provided with a series of openings 7, a series of tubes 8 provided with caps received within said openings and sockets, a bail-shaped retainer 13 having its side members pivoted to the side members of the frame and its cross-member normally extending over the

caps of the tubes, and yielding locking means 14, 15 on the frame and retainer for holding the latter in operative position.

3. A needle holder comprising a flat long block having openings extending inward from one of its long narrow sides, a series of needle tubes of varying depth received at their inner portions in said openings and having their ends remote from the block substantially in alinement, a frame having side members secured to the ends of said block and a cross-member provided with a series of openings receiving the outer portions of said tubes, caps on said tubes above said cross-piece, and a bail-shaped retainer frame hinged to the side members of the aforesaid frame and a cross-member normally lying over and adjacent said caps.

20 4. A needle holder comprising the combination of a block, a series of needle tubes received at their inner ends in said block, the needle compartments formed thereby extending varying distances into the block, a frame fixed to said block and having a cross-member with openings receiving the outer portions of the tubes, caps on the tubes, and a bail-shaped retainer frame hinged to said fixed frame and having a cross-member normally overlying said caps.

25 5. In a needle holder, a base block, a

series of needle tubes of varying lengths carried thereby, a frame having side members fixed to the base block and a cross-member with openings receiving the outer portions of the tubes, caps for said tubes, and a bail-shaped retainer frame hinged to said fixed frame and adapted to be positioned over said caps or to be swung downward to serve as an easel support.

30 6. A needle holder comprising the combination of a flat block, a row of needle tubes having their inner portions received in openings in one of the long narrow sides of the block, a frame fixed to the block and having a cross-member with openings receiving the outer portions of the tubes, caps on said outer portions, and a hinged bail-shaped retainer frame having a cross-member normally overlying said caps.

35 7. A needle holder comprising the combination of a block, a row of needle tubes inserted at one end therein, a frame fixed to the block and having a cross-piece with openings receiving the outer portions of the tubes, and a hinged bail-shaped retainer having a cross-piece normally overlying the outer ends of the tubes.

40 In witness whereof I have hereunto signed my name.

JOHN A. WILLIAMS.
